(57) **CLAIM**

The ornamental design for an electric shaver, as shown and described.

DESCRIPTION

FIG. 1 is a front perspective view of an electric shaver showing my new design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The broken lines shown in FIGS. 1-3, 5, and 7 represent portions of the electric shaver that form no part of the claimed design. The dash-dot broken line in FIG. 7 depicts the boundary of the claim and forms no part of the claimed design.

1 Claim, 7 Drawing Sheets
